UNITED STATES PATENT OFFICE.

ROMAIN DE BERSAQUES, OF SEATTLE, WASHINGTON.

VENDING-MACHINE.

1,199,352.

Specification of Letters Patent. Patented Sept. 26, 1916.

Application filed January 26, 1915. Serial No. 4,443.

To all whom it may concern:

Be it known that I, ROMAIN DE BERSAQUES, a citizen of the United States, residing at Seattle, in the county of King and 5 State of Washington, have invented a certain new and useful Improvement in Vending-Machines, of which the following is a specification.

My invention relates to improvements in 10 coin-controlled vending machines, and the object of my improvement is to provide a simple and efficient machine embodying a receptacle for articles of merchandise together with mechanism that is adapted to be 15 actuated to permit the emission of one of such articles from such receptacle to make it accessible to purchaser when such purchaser drops a coin of required value within a chute that forms a part of such mechanism. I attain this object by devices illustrated in the accompanying drawings 20 wherein—

Figure 1 is a view in front elevation of a structure embodying my invention with 25 its front wall removed; Fig. 2 is a view of the same in vertical section on broken line x, x of Fig. 1, with said front wall in its position; Fig. 3 is a view in vertical section on broken line y, y of Fig. 2, showing internal parts of my invention; and Fig. 4 is 30 an enlarged fragmentary view in vertical section on broken line z, z of Fig. 3, of details of my invention.

Like reference numerals indicate like 35 parts throughout the accompanying drawings wherein I have illustrated my invention as embodied in a cylindrical structure preferably of sheet metal within which is rotatably mounted a drum that is subdivided 40 into a plurality of compartments by radially disposed partitions, each of such compartments being adapted to have an article of merchandise that is to be offered for sale stored therein, such drum being adapted to 45 be automatically rotated through an angle equal to the angle between two of its adjacent radial partitions in response to the insertion of a coin in such machine to make accessible one at a time the articles of merchandise contained therein.

Referring to the drawings 5 is a cylindrical casing within which is disposed the operating and dispensing mechanism of my vending machine and 6 is a cover plate that is adapted to 55 cover the entire front side of the casing 5, such cover plate being preferably of glass

to permit the purchaser to see the articles stored therein and being removably secured to the casing 5 whereby access to the inside of the machine may be freely had for the purpose of refilling such machine when its stock of merchandise is sold out.

Within the casing 5 and concentric therewith is a rotatably mounted package carrying device consisting in a flat disk 7 that is provided with a concentrically disposed outwardly projecting drum 8 of smaller diameter than such disk 7 and with a plurality of partitions 9 that are secured thereto and extend radially outward, like the 65 spokes of a wheel, from the drum 8 to the periphery of the disk 7 to coact with such disk 7 and the cover plate 6 and form compartments, as more clearly shown in Fig. 1, within which may be stored articles of merchandise, as bags 10 of salted peanuts or candy that are to be sold, such bags 10, when the package carrying device is rotated, dropping downwardly through a slot 11 in the casing 5 into a lower open compartment 80 12 from which the articles may be removed one at a time by the purchaser and the package carrying device being controlled by mechanism hereinafter described whereby it may be rotated sufficiently to drop one of 85 the bags 10, only, by the insertion of a coin of a required value.

The disk 7 is journaled on a fixed shaft 13 that is secured to the back face of the casing 5 and projects forwardly therefrom, such shaft 13 also serving as a bearing shaft for a rotatably mounted sleeve 14 within the enlarged inner end 15 of which is disposed a flat spiral spring 16 one end of which is secured to the sleeve 14 by a screw 90 17 and the other end of which is secured to the disk 7 by a pin 18 whereby the spring 16 may be wound up like a clock spring by holding the disk 7 and turning the sleeve 14, such spring then being adapted to exert a 95 force to turn the disk 7 when the sleeve 14 is locked in a fixed position.

For the purpose of winding the spring 16 and locking it to the shaft 13 I have provided on the end of the sleeve 14 a fixedly 100 secured thumb nut 19 by which such sleeve 14 may be turned and on the end of the shaft 13 a fixedly secured ratchet wheel 20 that is adapted to be engaged by a spring 110 pressed pawl 21 on the thumb nut 19 to permit such thumb nut 19 and the sleeve 14 to be turned in one direction and to prevent

them from being turned in an opposite direction whereby stress may be brought on the spring 16 to turn the disk 7, there being secured to the outside surface of the disk 7 a concentrically disposed toothed escapement wheel 22 that is engaged by an escapement pawl 23, as more clearly shown in Fig. 3 whereby the disk 7 may turn only when the wheel 22 is released by the pawl 23, whereby such wheel 22 is released by the pawl 23 only momentarily to permit the disk 7 to move a distance equal to the space between two adjacent partitions 9 to discharge one bag 10 into the receptacle 12.

15 The pawl 23 may be moved to release the wheel 22 by inserting a coin 24 in a coin slot 26 and permitting such coin to follow downwardly along a chute 25 until it rests against an upwardly projecting arm 27 on the escapement pawl 23, as clearly shown in Fig. 3, in which position it will remain until a downward pressure is exerted on a thrust arm 28 to force such coin downwardly past the arm 27 and move such arm 28 to one side thus lifting the end 29 of the pawl 23 and permitting the wheel 22 and the disk 7 to move sufficiently to release one of the bags 10, the coin 24 following the chute 25 downwardly as will be clearly understood from an inspection of Fig. 3, and dropping in a coin receiving tray 30 provided in a receptacle 31 exteriorly of the casing 5, which tray 30 may be easily removed by turning a key 32 in a lock 33, such lock 33 being adapted to lock the tray 30 and the cover plate 6 to the casing 5, as shown in Fig. 2. A cross wall 34 is provided in the drum 8 near the outer end thereof such cross wall being concentrically 40 journaled on the sleeve 14 thus serving to support the outer end of the package discharging mechanism on the plate 7.

45 The front side of the coin chute 25 is open, as shown in Fig. 3, and the top end of such chute is preferably set in an inclined position, as more clearly shown in Fig. 4, whereby small articles, as matches, toothpicks and the like, that may be thrust through the slot 11 will drop out of the chute 25 instead of following down such chute.

50 The operation of the pawl 23 is simple there being provided, on that portion opposite the end 29, a curved surface 35 that engages with a tooth of the wheel 22 to depress the end 29 as soon as the wheel 22 begins to move and cause such end 29 to engage with the tooth next adjacent to the one it released when the coin 24 was thrust 55 downwardly thus permitting the wheel 22 to travel only the distance between two ad-

jacent teeth each time it is released, there being further provided a spring pressed pawl 33, as shown in Fig. 3, to prevent the escapement wheel 22 from being turned 65 backward.

When in use my vending machine is secured to a fixed support in an upright position, as shown in Fig. 1, and bags 10 or other articles of merchandise are inserted in the several spaces between the partitions 8, the spring 16 is then tightly wound by turning the thumb nut 19 and the cover 6 is secured thereon.

70 If a coin 24, as a nickel five cent piece, is inserted in the slot 26 and allowed to drop downwardly against the arm 27, as shown in Fig. 3, and the thrust arm 28 is pushed downwardly to force the coin 24 past the arm 27 such arm 27 will be moved outwardly and will cause the pawl 23 to release the tooth of the wheel 22 with which it is engaged thus permitting the spring 16 to rotate the wheel 22 and the disk 8 through a distance equal to one division of the disk 85 7 or to the distance between two adjacent partitions the pawl 23 engaging the next adjacent tooth of the escapement wheel 22 and stopping the disk 7 before more than one bag 10 is ejected.

90 Manifestly changes in the details and the form of construction of the various parts embodied in my vending machine may be made without departing from the spirit of my invention or sacrificing any of its advantages.

95 What I claim is:

In a vending machine of the class described, a casing provided with an outlet opening in one side thereof, a carrier rotatably mounted within said casing, a shaft supported at one of its ends and upon which the carrier is mounted, said carrier being divided into a plurality of separate compartments, a sleeve journaled on said shaft, 100 a housing formed on one end of said sleeve, a band spring within the housing secured at one end to said sleeve and secured at its other end to said carrier, a pawl carried by said sleeve and a ratchet carried by said shaft adapted to be operated to place the spring under tension, and escapement mechanism associated with said carrier whereby the carrier is given a step by step movement.

105 In witness whereof, I hereunto subscribe my name this fourteenth day of January, A. D., 1915.

ROMAIN DE BERSAQUES.
